ARTHUR E. ERICKSON, OF BROOKLYN, NEW YORK

WRENCH

Application filed September 7, 1929. Serial No. 390,920.

This invention relates to wrenches and has for its object the provision of an improved wrench. More particularly, the invention aims to provide an improved adjustable wrench of the open end or sliding side jaw type.

The heretofore customary wrenches of the adjustable sliding side jaw type sacrifice some vital feature such as strength, rigidity, durability or compactness in order to attain the adjustable feature. Most commonly in order to obtain an easily adjustable feature these wrenches sacrifice strength and rigidity.

15 Frequently adjustable wrenches of this type do not provide any method of locking the adjustable member in fixed relation to the body of the wrench. The force of gravity or frictional resistance is customarily relied upon to hold the jaws in fixed relation. This type of wrench when being used manually frequently falls out of adjustment and must be reset usually at inopportune times. Due to the adjustable feature many wrenches also 25 spring slightly under stress and as a consequence the jaws do not fit snugly against the flat sides of the object being turned, thus causing a greater than normal strain on the jaws and an insecure feel when the jaws are 30 first contacted with the object to be turned.

The present invention contemplates the provision of an improved adjustable wrench which has substantially all the strength, rigidity, durability and compactness of the 35 customary open end or set wrench. This result is obtained by forming the body or handle of the wrench and one jaw of an integral piece of metal, to wit, of a forged piece of steel. As a part of the handle and fixed jaw 40 and extending at a right angle thereto there is provided an angular shoulder which acts as a brace to absorb most of the stress encountered in use.

45 The movable or adjustable jaw has an angular shoulder which registers with the angular shoulder on the handle. The adjustable jaw is also provided with a member extending along the handle of the wrench in a countersunk portion thereof. This member 50 is provided with projecting lugs adapted to

register with depressions in the bottom of the countersunk portion of the handle of the wrench.

The adjustment of the wrench is accomplished by raising the adjustable jaw bodily so that the lug projections in the adjustable member clear the depressions on the body of the wrench and again lowering the adjustable jaw into registering relation with different depressions. Thus the space between the 55 jaws of the wrench is changed and it is possible to place the adjustable jaw in a plurality of fixed positions.

60 The invention will be better understood by consideration of the following description 65 in conjunction with the accompanying drawing in which:

Figure 1 is a top plan, partially in section, of the wrench assembly;

Fig. 2 is a sectional view of the assembly; 70

Fig. 3 is a plan of the adjustable jaw; and

Figs. 4 and 5 are details of special features.

A body or handle 10 of the wrench is provided with a fixed jaw 11. Extending at right angles to the face of the fixed jaw 11 is 75 a shoulder 12 against which bears a corresponding shoulder 13 of an adjustable jaw 14. The main operating stress of the wrench is transmitted through these shoulders so that in actual operation there is little likelihood 80 of the adjustable jaw springing out of position.

The adjustable jaw 14 is provided with a member 15 extending along the shank of the wrench. Projecting from the bottom of the member 15 of the adjustable jaw 14 are lug 85 projections 16 which register with depressions 17 in a countersunk portion on the body or handle 10 of the wrench. During the operation of the wrench a portion of the stresses are transmitted from the adjustable jaw 14 to the body of the wrench by means of the registering depressions 17 and the lug projections 16. The adjustment of the jaws of the wrench for different openings is accomplished by raising the adjustable jaw 14 so that the lug projections 16 carried thereby are not in registered relation with the depressions 17 on the handle of the wrench. The adjustable jaw is then moved into the desired posi- 90 95 100

tion and again seated so that the depressions 17 and lugs 16 are in registered relation.

Transversely across the top of the member 15 of the adjustable jaw are two countersunk 5 grooves 18 with tapered sides. These grooves register with two corresponding ridges 19 on the lower portion of a movable cover 23. The cover or plate 23 is held in registered relation with the member 15 of the adjustable 10 jaw 14 by means of a screw clamp device.

Extending across the countersunk portion of the wrench and raised slightly above the surface thereof, is a metal strap 21. A threaded hole 20 in the center of the strap 21 15 is adapted to engage a screw 22. The lower extremity of screw 22 registers with a depression 24 in the center of the upper side of the cover or plate 23.

The sides of the plate 23 are bevelled. 20 These bevelled sides of the plate 23 register when seated with a corresponding bevel 25 provided on the rim of the countersunk depression in the handle of the wrench and with a bevelled shoulder 26 provided on the upper 25 side of the adjustable jaw 14.

When the screw 22 is screwed into registering relation with the plate 23, plate 23 performs a plurality of functions. Primarily, this plate holds the adjustable jaw in fixed 30 registered relation with the body or handle of the wrench by means of the lug projections 16 on the adjustable jaw and the depressions 17 in the bottom of the countersunk portion of the handle. Aside from this, the forward 35 extending bevelled edge of the plate 23 bears against the bevelled shoulder 26 of the adjustable jaw. By means of this action, a portion of the operating stresses are transmitted from the adjustable jaw to the body of the wrench and the adjustable jaw is thus held firmly against any sidewise thrust which might be encountered should the wrench tilt during a turning operation.

The bevelled sides of the plate 23 also assure the proper seating of the plate 23 so 45 that it will be always in registered relation with the adjustable jaw 14. The bevelled sides of the plate also provide a means of maintaining the plate in a plane parallel to the axes of the wrench handle, even when the adjustable jaw is at one extremity of its adjustable position.

I have found it advantageous in the practice of the invention to counter-sink portions 50 in the body of the wrench so that the adjustable jaw fits into this countersunk portion. When the adjustable jaw is in operating position and so clamped there are no 55 projecting edges above the body of the wrench except the clamping screw 22 and its supporting strap 21.

There is substantially no sacrifice of 60 strength when the adjustable jaw is held in position in this manner for the adjustable jaw has sufficient bearing surfaces against the

body of the wrench, such, for example, as the shoulders 12 and 13 which are in registering relation as well as the lugs 16 and depressions 17. Aside from these features which provide strength and rigidity to the adjustable jaw, one side of the member 15 of the adjustable 70 jaw bears against the side walls of the countersunk portion in the handle of the wrench when the adjustable jaw is in an extreme position. Thus when the adjustable jaw is in 75 position and the wrench in operation, the stresses of operation are transmitted from the adjustable jaw to the body of the wrench at many different points, avoiding any undue strain on the bearing portions of the 80 wrench.

The bevelled shoulder 26 bearing against the cover or plate 23 also serves to transmit a certain portion of the stresses of operation to the handle of the wrench. This shoulder 85 also assures the adjustable jaw being held in a rigid position during operation.

The clamping of the adjustable jaw in position substantially inhibits the possibility of play developing so that the adjustable jaw 90 does not spring out of position and as a consequence an adjustable open end wrench is provided with all the features of rigidity, strength and durability of the customary set open end wrench.

A single adjustable, open end wrench of 95 this type fulfills all the operations and uses of a set of four double ended set open end wrenches. Aside from this the present wrench is no more cumbersome or heavy than the customary set wrench, for due to the countersunk features of the adjustable jaw 100 it is not necessary to use any more metal in the wrench than is customary in the usual type of set wrench.

I claim:

1. A wrench comprising a handle having a fixed jaw, an adjustable jaw, a countersunk depression adjacent one end of the handle having therein pairs of lug depressions 110 adaptable to register with pairs of lug projections on a supporting member of the said adjustable jaw, and a cover adapted to hold the said adjustable jaw in fixed registered relation with the said handle, bevelled sides on the said cover adapted to automatically seat the cover in registered relation with the handle of the wrench and the adjustable jaw.

2. A wrench comprising a handle having a fixed jaw, an adjustable jaw, lug depressions 115 in the handle adapted to register with lug projections on a supporting member of the adjustable jaw and a tapered shoulder on the said adjustable jaw adapted to register with a tapered side of a clamping cover whereby side thrusts are transmitted from the said adjustable jaw to the body of the wrench.

3. A wrench comprising a handle having a fixed jaw, an adjustable jaw, lug depressions 120 in the said handle adapted to register

with lug projections on a supporting member of the adjustable jaw, grooves on the adjustable jaw registering with ridges on a clamping cover whereby working stresses are transmitted from the adjustable jaw to the body of the wrench and whereby the adjustable jaw is kept in alignment when not clamped in registering position.

4. A wrench comprising a handle having a fixed jaw, an adjustable jaw, lug depressions in the handle adapted to register with lug projections on a supporting member of the adjustable jaw and a tapered shoulder on the said adjustable jaw adapted to register with a tapered side of a clamping cover whereby side thrusts are transmitted from the adjustable jaw to the body of the wrench, grooves on the said adjustable jaw registering with ridges on a clamping cover whereby working stresses are transmitted from the adjustable jaw to the body of the wrench and whereby the adjustable jaw is kept in alignment when not clamped in registering position, and a square shoulder on the said adjustable jaw registering with a corresponding square shoulder on the handle of the wrench whereby direct working stresses are transmitted from the adjustable jaw to the body of the wrench.

5. An open-ended wrench comprising a handle portion having at least one end thereof enlarged, one side of the enlarged end being formed into a gripping portion, said handle having a longitudinal countersunk recess extending inwardly from the enlarged end, the outer face of the side of the enlarged end remote from the gripping portion having a countersunk recess extending substantially normal to and connecting with the countersunk recess of the handle portion, a substantially L-shaped adjustable jaw slidably mounted in said recesses and having its gripping portion engaging the inner wall defining the recess in the outer face of the enlarged end, whereby working stress is transmitted directly from the gripping portion to the handle, one leg of the L-shape therefore overlying the main handle portion and having means for directly interlocking therewith, and means adapted to positively hold the adjustable jaw in fixed relation to said handle.

6. An open-ended wrench comprising a handle portion having at least one end thereof enlarged, one side of the enlarged end being formed into a gripping portion, said handle having a longitudinal countersunk recess extending inwardly from the enlarged end, the outer face of the side of the enlarged end remote from the gripping portion having a countersunk recess extending substantially normal to and connecting with the countersunk recess of the handle portion, a substantially L-shaped adjustable jaw slidably mounted in said recesses and having its gripping portion engaging the inner wall defin-

ing the recess in the outer face of the enlarged end, whereby working stress is transmitted directly from the gripping portion to the handle, one leg of the L-shape therefore overlying the main handle portion, cooperating depressions and projections on said sliding jaw and handle for determining the various positions of adjustment of the adjustable jaw with respect to the fixed jaw, and means for maintaining the projections in depressions whereby a set adjustment may be maintained.

7. An open-ended wrench comprising a handle portion having at least one end thereof enlarged, one side of the enlarged end being formed into a gripping portion, said handle having a longitudinal countersunk recess extending inwardly from the enlarged end, the outer face of the side of the enlarged end remote from the gripping portion having a countersunk recess extending substantially normal to and connecting with the countersunk recess of the handle portion, a substantially L-shaped adjustable jaw slidably mounted in said recesses and having its gripping portion engaging the inner wall defining the recess in the outer face of the enlarged end, whereby working stress is transmitted directly from the gripping portion to the handle, one leg of the L-shape therefore overlying the main handle portion, cooperating depressions and projections on said sliding jaw and handle for determining the various positions of adjustment of the adjustable jaw with respect to the fixed jaw, and a cover for maintaining the projections in depressions wherein a set adjustment may be maintained.

8. An open-ended wrench comprising a handle portion, a fixed jaw integral with said handle portion, the end of the handle portion adjacent the jaw having a substantially L-shaped countersunk recess, a substantially L-shaped adjustable jaw slidably mounted in said countersunk recess, the outer portion of said jaw being the gripping portion, said adjustable jaw having a face of its gripping portion substantially normal to the gripping face thereof which slidely engages a face of the wall defining the L-shaped recess in the handle portion to transmit working stress directly from the gripping portion of the adjustable jaw to the handle portion, one leg of the L-shape therefore overlying the main handle portion and having means for directly interlocking therewith, and means adapted to positively hold the adjustable jaw in fixed relation to said handle.

9. An open-ended wrench comprising a handle portion, a fixed jaw integral with said handle portion, the end of the handle portion adjacent the jaw having a substantially L-shaped countersunk recess, a substantially L-shaped adjustable jaw slidably mounted in said countersunk recess, the outer portion of said jaw being the gripping portion, said ad-

- justable jaw having a face of its gripping portion substantially normal to the gripping face thereof which slidably engages a face of the wall defining the L-shaped recess in the handle portion to transmit working stress directly from the gripping portion of the adjustable jaw to the handle portion, one leg of the L-shape therefore overlying the main handle portion, cooperating depressions and projections on said sliding jaw and handle for determining the various positions of adjustment of the adjustable jaw with respect to the fixed jaw, and means maintaining the projections in depressions whereby a set adjustment may be maintained.
- 10 15 10. An open-ended wrench comprising a handle portion, a fixed jaw integral with said handle portion, the end of the handle portion adjacent the jaw having a substantially L-shaped countersunk recess, a substantially L-shaped adjustable jaw slidably mounted in said countersunk recess, the outer portion of said jaw being the gripping portion, said adjustable jaw having a face of its gripping portion substantially normal to the gripping face thereof which slidably engages a face of the wall defining the L-shaped recess in the handle portion to transmit working stress directly from the gripping portion of the adjustable jaw to the handle portion, one leg of the L-shape therefore overlying the main handle portion, cooperating depressions and projections on said sliding jaw and handle for determining the various positions of adjustment of the adjustable jaw with respect to the fixed jaw, and a cover maintaining the projections in depressions whereby a set adjustment may be maintained.
